No Drawing. 7 Pages Specification

Certain halogenated compounds represented by the formula

wherein

C_nH_{2n-2} is a saturated hydrocarbon chain;

n represents an integer selected from 2 through 4;

m and m' each represent an integer selected from 1, 2 or 3, provided that sum of $m+m'$ is at least equal to 4;

and

X and Y represent chloro or bromo,

are prepared by reduction of the corresponding diketones. The halogenated aralkanols effectively control the growth of microorganisms.
